CYCLE FAIRING

William L. Mitchell, 760 Kennebec Court, Bloomfield Hills, Mich. 48013, and David R. North, 26240 Warner Ave., Warren, Mich. 48091

Filed Sept. 10, 1974, Ser. No. 504,837

Term of patent 7 years

Int. Cl. D12—11
U.S. Cl. D12—110

FIG. 1

FIG. 2

FIG. 3

FIG. 4

FIG. 5

FIG. 6

FIG. 7

FIG. 1 is a perspective view of a cycle fairing showing our new design, it being understood that broken lines are for illustrative purposes only,

FIG. 2 is a rear elevational view thereof,
 FIG. 3 is a front elevational view thereof,
 FIG. 4 is a right side elevational view thereof,
 FIG. 5 is a top plan view thereof,
 FIG. 6 is a left side elevational view thereof, and
 FIG. 7 is a bottom plan view thereof.

We claim:

The ornamental design for a cycle fairing, as shown.
